CLARENCE E. TYLER, OF NEWARK, NEW JERSEY, ASSIGNOR TO S. E. T. VALVE & HYDRANT COMPANY, NEW YORK, INC., OF NEW YORK, N. Y., A CORPORATION OF NEW YORK.

CURB-BOX.

1,081,281.

Specification of Letters Patent.

Patented Dec. 9, 1913.

Application filed February 8, 1913. Serial No. 747,147.

To all whom it may concern:

Be it known that I, CLARENCE E. TYLER, of Newark, Essex county, New Jersey, have invented a new and useful Improvement in 5 Curb-Boxes, of which the following is a full, clear, and exact description.

My invention relates to improvements in curb boxes or surface boxes such as are adapted to be attached to the end of a stand 10 pipe connecting with a suitable sub-surface valve. Such boxes are used in order to securely lock the stand pipe to prevent it from being filled with dirt, water, or refuse. These boxes are made generally from cast 15 ings, because the structure on which they are used is rough and cheap, and it is essential that the boxes be constructed in such a manner that all the parts can be cast to preserve simplicity and cheapness, and it is also 20 requisite that the cover to the box fit snugly, and have a convenient means for locking it in place and for removing it to get access to the stand pipe and valve. It is also necessary in the trade to have the parts fit sufficiently tight to afford a suitable cover, and 25 that this be done without any machine work on the parts, as machining makes the parts too expensive for the use intended.

The object of my invention is to produce 30 a strong, simple and reliable box meeting all the above requirements, to provide a safe, strong, and easily operated lock for the cover of the box, and incidentally to provide a drain so that if any water seeps into 35 the box it will find its way into the pipe below. In carrying out the above idea, I have also provided an unusually strong pipe connection for the box, which will prevent the threads of the pipe where it connects with 40 the box, from being easily broken.

Reference is to be had to the accompanying drawings forming a part of this specification, in which similar reference characters indicate corresponding parts in all the views. 45 Figure 1 is a vertical cross section of the box showing my improvements. Fig. 2 is a plan view of the box with the cover removed. Fig. 3 is an inverted plan of the cover, and Fig. 4 is a broken vertical section of a slightly modified form of the box, 50 in which the structure is made in two parts.

The box 10 is exteriorly of the usual shape, and it has the customary extension 11 on the bottom in which the top of a stand 55 pipe is inserted. The extension is threaded

as shown at 12 to provide for connection with a stand pipe, and the diameter of the thread is gradually reduced toward the top, and the thread portion is spaced above the lower edge of the extension so that the stand 60 pipe can have its full diameter extended into the part 11, while the threaded portion of the pipe will engage the thread 12 of the box.

Within the box and rising from the bottom thereof is an annular rib 13 having outwardly extending flanges 13^a at the top, which flanges are spaced apart as shown in Fig. 2, leaving a space 14 between the flanges 13 to provide for the locking engagement of the cover, as presently described. The rib 13 is pierced on a level with the box bottom as shown at 15, so that any water which seeps into the box 10 can find its way through into the pipe below, and to prevent any dirt from falling through into the pipe when the cover 18 is removed, a second cover 16 fits loosely over the top of the extension 11 and within the annular rib 13. This cover can be provided with a hold 70 17 to which a tool or the fingers may be applied to remove it. The cover 16 fits loosely, and as the parts are castings, and not especially smooth, any water that finds its way through the opening 15 will also find its way beneath the cover.

The important feature of the invention lies in the connection between the box cover 18 and the rib 13. This cover has a depending web 19 which is annular, and lies within the periphery of the cover so that it can readily drop into the box 10, and at the lower edge of the web 19 are inturned flanges 20 which are spaced apart as shown in Fig. 3, so that when the cover is arranged to bring the flanges 20 opposite the spaces 14 between the flanges 13^a above referred to, the cover can be dropped to place. Then by giving the cover a turn, the flanges 20 are locked securely between the flanges 13^a. If desired the flanges 13^a and flanges 20 can be inclined or cam shaped, to make them lock more tightly. The cover 18 can have any usual means to facilitate its turning, and I have shown it with a basin-like depression in the top in which is located a lug 22 to receive a wrench.

In Fig. 4 I have shown a modification in which the box structure is unchanged, except that the box is made in two parts, divided on the bottom. This makes a structure 110

which can be cast rather more conveniently than where the box is made in a single piece, but it will be noted that the arrangement of parts is the same as already described. In 5 making the two-part box, the bottom between the rib 13 and the side wall of the box, is made of overlapping flanges 23 and 24, which are fastened together by bolts or rivets 25, or equivalent fastenings. When 10 this arrangement is used, the middle portion of the box can be pushed up through the bottom opening, and the meeting flanges 23 and 24 simply bolted together.

From the foregoing description it will be 15 seen that the structure which I have shown and described is of the greatest simplicity and cheapness, that the parts can all be cast, and that it is a very simple matter to lock the cover 18 in place and to remove it if 20 desired.

It will also be noticed that when my improved box is screwed to the top of a pipe, the bottom of the box is absolutely sealed so 25 that there is no chance for dirt or other foreign matter to work in from the bottom, and as the flange of the top or cover lies flat against the upper edge of the box and the cover is securely locked in place, the box 30 is thoroughly sealed and the parts cannot easily become disarranged.

I claim:—

1. A curb box open at the top and provided with a lower extension adapted for a 35 pipe connection, a raised annular rib rising from the floor of the box around the pipe opening, said rib having lateral flanges spaced apart from each other, said rib also being provided with drainage openings therethrough, and a cover adapted to lie on the top of the box, said cover having depending flanges spaced apart and provided with 40 inturned portions adapted to drop between

the aforesaid rib flanges and then be turned into locking engagement with said flanges.

2. A curb box adapted to connect with a 45 stand pipe, said box having a raised annular perforated rib on the floor thereof, said rib being provided with lateral flanges spaced apart from each other, a loose cover lying within the aforesaid rib, and a main cover 50 adapted to lie on the box top, said main cover having depending inturned flanges adapted to drop between the aforesaid box flanges and be turned into locking engagement beneath said box flanges. 55

3. A curb box open at the top and provided at the bottom with a reduced extension adapted for a pipe connection, a raised annular rib rising from the floor of the box around the pipe opening, said rib being 60 spaced apart from the side walls of the box and having lateral flanges spaced apart from each other, and a cover adapted to lie flat on the box top, said cover having depending flanges spaced apart and provided with in- 65 turned portions adapted to drop between the aforesaid rib flanges and then be turned into locking engagement with the said rib flanges.

4. A curb box open at the top and provided with a separable floor having a pipe 70 connection on the under side and a raised annular rib on the inner side, said rib being spaced apart from the side walls of the box and having laterally extending flanges 75 spaced apart from each other, and a cover for the box, said cover having depending flanges spaced apart and provided with in-turned portions adapted to drop between the aforesaid rib flanges and then be turned into locking engagement with said rib flanges.

CLARENCE E. TYLER.
